UNITED STATES PATENT OFFICE

112,182

DESIGN FOR A BENCH

Frank James Schmitt, San Diego, Calif.

Application November 24, 1936, Serial No. 66,124

Term of patent 14 years

To all whom it may concern:

Be it known that I, Frank James Schmitt, a citizen of the United States, residing at San Diego, in the county of San Diego and State of California, have invented a new, original, and ornamental Design for a Bench, of which the following is a specification, reference being had to the accompanying drawing, forming part thereof.

I claim:—

The ornamental design for a bench, as shown

FRANK JAMES SCHMITT.
